UNITED STATES PATENT OFFICE.

WILLARD W. KESTER, OF LOS ANGELES, CALIFORNIA.

HOT-VAPOR GENERATOR.

1,293,115.

Specification of Letters Patent.

Patented Feb. 4, 1919.

Application filed April 15, 1918. Serial No. 228,771.

To all whom it may concern:

Be it known that I, WILLARD W. KESTER, a citizen of the United States, residing at Los Angeles, in the county of Los Angeles 5 and State of California, have invented new and useful Improvements in Hot-Vapor Generators, of which the following is a specification.

My object is to make a hot vapor generator for use in killing gophers, rats, squirrels and the like, by forcing the vapor into the holes or dens. My vapor generator may 10 also be used for fumigating dwellings and the like, burning stumps of trees and testing irrigation canals.

My invention consists in the construction and arrangements of parts hereinafter shown and described.

Figure 1 is a front elevation of a hot 20 vapor generator embodying the principles of my invention and looking in the direction indicated by the arrow 1 in Fig. 2.

Fig. 2 is a side elevation looking in the direction indicated by the arrow 2 in Fig. 1.

Fig. 3 is an enlarged fragmentary sectional detail on a plane parallel with Fig. 2 and on the line 3—3 of Fig. 1.

Fig. 4 is a fragmentary horizontal sectional detail on the line 4—4 of Fig. 2 and looking downwardly.

The base 1 which is made of sheet iron and has an inclined top 2, ends 3 supporting the ends of the top and a high front wall 4 and a low rear wall 5 supporting the sides 35 of the top. Air holes 6 are formed through the walls 3, 4 and 5. A pipe nipple 7 has a flange 8 upon its lower end and said pipe nipple is inserted upwardly through the top 2. A baffle plate 9 is inserted upwardly 40 against the flange 8 and secured in place by rivets 10, to hold the nipple rigidly in place. A circular opening 11 is formed through the baffle 10, and a burner is mounted centrally 45 in the opening 11, said burner comprising a circular cup 12, a pad of asbestos 13 against the inner side of the bottom of the cup, a washer 14 upon the pad, a crossbar 15 under the cup and a bolt 16 inserted downwardly 50 through the washer 14, pad 13, cup 12 and cross-bar 15. The ends of the cross-bar 15 are secured to the baffle 9; said cross-bar extending diametrically across the hole 11. Arms 17 and 18 are secured to the end pieces 3 at their highest points and extend upwardly a considerable distance. Tanks 19 55 and 20 are mounted between the upper ends

of the arms 17 and 18 and a bail 21 connects the upper ends of the arms, for carrying the device. The tanks 19 and 20 are built together, there being a partition 20' for 60 separating the two chambers of the tanks.

The tank 19 is adapted for carrying a supply of fuel oil, such as kerosene. A needle valve 22 leads from the bottom of the tank and a pipe 23 leads from the needle valve 65 and discharges into the cup 12 upon the asbestos pad 13.

The smoke stack 24 fits upon the nipple 7, there being registering slots 25 and 26 in the nipple and smoke stack. The generator 27 is centrally located in the lower end of the smoke stack 24, said generator being an annular body having a chamber 28 and a central opening 29. The feed pipe 30 is tapped into a reducer bushing 30' and the bushing is tapped into the lower end of the generator and the feed pipe 30 extends through the slots 25 and 26. The check valve 31 is fixed upon the feed pipe 30. An elbow 32 is screwed into the check valve. 70 A regulating valve 33 is screwed into the elbow and connected to the bottom of the tank 20. The tank 20 is adapted to contain suitable distillate oil for producing a vapor for destroying the gophers, squirrels, rats and any burrowing rodents, or any other volatile liquid suitable for generating a vapor for fumigating and the like. 75

A nipple 34 is tapped into a reducer bushing 34' and the bushing is tapped into the 90 generator 27 at the top of the chamber 28. A cap 35 is screwed upon the nipple and has a discharge orifice 36, thereby producing a nozzle for the discharge of the vapor. The vapor pipe 37 is pushed over the nozzle 35 95 and held in place by a hook and eye 38 and the other end of the pipe 37 may be inserted into the gopher hole, den or the like.

The needle valve 22 is operated to allow oil to run into the cup 12. The oil is lighted 100 and burns upwardly against the bottom of the generator 27 and through the opening 29 and around the generator within the smoke stack. The valve 33 is opened to fill the generator 27 to the desired extent with the 105 vapor producing oil and as the generator becomes hot, the vapor produced will be discharged through the orifice 36 and into the pipe 37 and into the gopher hole or the like. As the pressure increases in the generator 110 27 the check valve 31 will hold and the pressure will be directed through the nozzle.

My apparatus may also be used for fumigating trees, dwellings or chicken houses, and for general purposes, wherever it is desired to generate quickly a suitable vapor. 5 For instance, it may be used for burning stumps. In the last case, an inflammable vapor is generated which is ignited, and which burns like a torch, quickly reducing the stump. In testing irrigation canals, the 10 vapor may be injected into cracks or leaks, and the extent of the same may be easily ascertained by the vapor or fumes issuing from the ground.

Various changes may be made in the 15 tails of construction without departing from the spirit of my invention, as claimed.

I claim:

1. A vapor generator for killing gophers and the like, comprising an inclined sheet 20 iron top, end pieces supporting the ends of the top, a high front wall extending from one side of the top, a lower rear wall extending from the other side of the top; there being air holes through the walls and a pipe 25 hole through the top; a pipe nipple inserted upwardly through the pipe hole and having a flange forming a stop, a baffle plate inserted upwardly against the flange and secured to the top; there being a circular opening 30 at the center of the baffle plate; and a burner mounted centrally in the opening; said burner comprising a circular cup, a pad of asbestos upon the bottom of the cup, a washer upon the pad, a cross-bar under 35 the cup, and a bolt inserted downwardly through the washer, pad, cup and cross-bar; said cross-bar being attached to the baffle plate to support the burner.

2. A vapor generator for killing gophers 40 and the like, comprising a base having a pipe opening, a pipe nipple inserted upwardly through the pipe opening and having a flange engaging the base, a baffle plate inserted upwardly against the flange and secured to the base and having a circular 45 opening, a cup burner mounted in the circular opening, means for supplying liquid fuel to the burner, a smoke stack mounted upon the nipple; there being registering slots 50 extending downwardly from the upper end

of the nipple and upwardly from the lower end of the smoke stack; a generator mounted in the smoke stack and having a feed pipe extending through the registering slots and a discharge pipe extending through the opposite side of the smoke stack, a tank connected to the feed pipe, and a nozzle upon the discharge pipe. 55

3. A vapor generator for killing gophers and the like, comprising a base having a 60 pipe opening, a pipe nipple inserted upwardly through the pipe opening and having a flange engaging the base, a baffle plate inserted upwardly against the flange and secured to the base and having a circular 65 opening, a cup burner mounted in the circular opening, means for supplying liquid fuel to the burner, a smoke stack mounted upon the nipple; a generator mounted in the smoke stack and having a feed pipe extending through one side of the smoke stack 70 and a discharge pipe extending through the opposite side of the smoke stack, a tank connected to the feed pipe, a nozzle upon the discharge pipe, and a flexible vapor pipe 75 pushed over the nozzle and held in place by a hook and eye.

4. A vapor generator for killing gophers and the like, comprising a base having an inclined top; there being a pipe hole through 80 the top; a pipe nipple inserted upwardly through the pipe hole and having a flange engaging the top, a baffle plate inserted upwardly against the flange and secured to the top, a cup burner mounted upon the baffle 85 plate, a smoke stack mounted upon the pipe nipple, a generator in the smoke stack, a supply pipe connected to one side of the generator, a discharge pipe connected to the other side of the generator, arms extending upwardly from the base, a fuel tank mounted upon the arms and connected to the burner, a generating liquid tank mounted on the arms and connected to the supply pipe, and a flexible vapor hose 90 connected to the discharge pipe. 95

In testimony whereof I have signed my name to this specification.

WILLARD W. KESTER.
